WITNESS:

WITNESS:

ATTORNEY

UNITED STATES PATENT OFFICE.

HENRY A. TRUXILLO, OF ELIZABETH, NEW JERSEY.

DENTAL INSTRUMENT.

Application filed March 22, 1924. Serial No. 701,171.

To all whom it may concern:

Be it known that I, HENRY A. TRUXILLO, citizen of the United States, residing at Elizabeth, in the county of Union and State 5 of New Jersey, have invented new and useful Improvements in Dental Instruments, of which the following is a specification.

This invention relates to dental instruments and more particularly to an instrument 10 for holding a length of dental floss or a piece of abrasive material for insertion between the teeth.

The principal object of the invention is to provide an instrument which may be quickly 15 associated with a strip of abrasive material used in the dental profession for insertion between the teeth for the purpose of packing a filling or burnishing and polishing the filling, or for cleaning purposes, and is particularly designed for this purpose when 20 working on teeth located in the back of the mouth and which are awkward to reach should the polishing strip be held in the fingers of the hand such as the case at the 25 present time.

Another object of the invention is to provide an instrument wherein the clamping jaws for holding a strip of material may be locked in clamping engagement by the compression of a pair of handles to a predetermined point, and whereby further compression of the handles will cause the jaws to separate to release the strip.

A still further object is to provide a dental instrument for the purpose mentioned 35 and which includes a pair of separable sections which may be quickly taken apart and sterilized for sanitary purposes.

With these and other objects in view, the 40 invention resides in certain novel construction and combination and arrangement of parts, the essential features of which are hereinafter fully described, are particularly pointed out in the appended claims, and are 45 illustrated in the accompanying drawing, in which:—

Figure 1 is a perspective view of my invention showing the jaws in open position.

Figure 2 is a perspective view of the parts 50 separated.

Figure 3 is a side elevation of the invention with the jaws in locked position.

Figure 4 is a longitudinal sectional view through the jaws.

Figure 5 is a transverse sectional view on the line 5—5 of Figure 3.

Referring more particularly to the drawing, the reference numeral 10 designates my invention in its entirety and which includes a pair of co-acting separable sections 11 and 12.

The section 11 is formed with a handle 13, one end of which is enlarged or broadened to form a head 14. The head 14 is bifurcated as at 15 and the furcated portions 16 are bent downward at their ends to provide jaws 17 for co-action with the jaws on the section 12 and which will presently be described. Soldered or otherwise secured to the inner surface of the handle 13 is a spring 18 formed of a length of relatively stiff wire having one of its ends bent upwardly as at 19 for pressing engagement with the section 12, the other end of the spring being bent upwardly and provided with a hook 20.

The section 12 is likewise provided with a handle 21 formed with a head 22 at one end of a size to fit between the furcations 16 of the section 11. The head is formed with a pair of shoulders 23 for engagement beneath the furcations 16 and which co-act with the furcations to fulcrum or pivot the sections one with the other. The head 22 is formed with a pair of downwardly extending jaws 24 for co-action with the jaws 17 as above mentioned. When the two sections are assembled as shown in Figure 1, it will be seen that the portion 19 of the spring 25 will serve to hold the jaws in separated position and upon compression of the handles, the jaws may be closed against the tension of the spring. When it is desired to clamp a strip of material A between the jaws for 30 insertion between the teeth, the handles are compressed in the manner just described to a predetermined point whereupon the hook 20 will be brought into engagement with any one of a plurality of teeth 25 formed in an enlargement 26 on a downwardly extending lug 27 carried by the underside of the handle 21, and whereby the two handles are locked in engagement with each other.

The enlargement 26 is provided with a cam surface 28 as shown in Figure 5 of the drawing, and when it is desired to release the strip of material from the jaws, the handles are further compressed or flexed to move the 35 40 45 50 55 60 65 70 75 80 85 90 95 100 105

hook to a position above the enlargement, and when passing over the uppermost tooth, the handle 13 is moved laterally when the hook clears the top of the enlargement. The 5 handle will then automatically spring back to its former position and in so doing, the hook will ride down the cam surface on the back of the enlargement by reason of the pressure exerted by the spring 18.

10 From the foregoing description, the construction and operation of the invention is believed to be fully set forth and it will be seen that when a strip of material such as above mentioned has been clamped between 15 the jaws, the instrument may be inserted into the mouth and is capable of reaching between the teeth in the back of the mouth and which are difficult to work upon under the present condition for the purpose of 20 cleaning or polishing the filling. When it is desired to separate the sections 11 and 12 for the purpose of sterilizing the instrument, the same may be easily removed by spreading the handles and moving the shoulders from beneath the furcations 16.

25 While I have described what I deem to be the most desirable embodiment of my invention, it is obvious that many of the details may be varied without in any way departing from the spirit of my invention and I therefore do not limit myself to the exact 30 details of construction herein set forth nor to anything less than the whole of my invention limited only by the appended 35 claims.

What is claimed as new is:—

1. An instrument of the class described comprising a pair of separate sections, spaced co-acting jaws formed on said sections, means for normally holding said jaws 40

in spaced relation to each other, and co-acting means for locking said jaws into clamping engagement with each other.

2. An instrument of the class described comprising a pair of separate sections, 45 spaced co-acting jaws formed on said sections, means for normally holding said jaws in spaced relation to each other, and co-acting means for locking said jaws into clamping engagement with each other, said last means comprising a hook member carried by one of said sections, and a depending lug having teeth formed on the other of said member for engagement by said hook member. 50

55 3. An instrument of the class described comprising a pair of co-acting separable sections, one of said sections being bifurcated to provide a pair of spaced jaws, the other of said sections formed with shoulders for engagement beneath the furcations of said first sections, and jaws formed on said last mentioned sections for co-action with said first mentioned jaws. 60

65 4. An instrument of the class described comprising a pair of co-acting separable sections, one of said sections being bifurcated to provide a pair of spaced jaws, the other of said sections formed with shoulders for engagement beneath the furcations of said first sections, and jaws formed on said last mentioned sections for co-action with said first mentioned jaws, means for normally forcing said jaws away from each other and means for locking said jaws in 70 closed position. 75

In testimony whereof I have affixed my signature.

HENRY A. TRUXILLO.
